(57) **CLAIM**

The ornamental design for an exit light, as shown and described.

DESCRIPTION

FIG. 1 is a perspective view of an exit light shown in a powered-off state of use

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is bottom plan view thereof; and,

FIG. 8 is a front elevation view of the exit light shown, in a powered-on state of use.

The broken lines in the drawings illustrate portions of the article and form no part of the claimed design.
